UNITED STATES PATENT OFFICE.

JOHN H. SHAW, OF NEW HAVEN, CONNECTICUT, ASSIGNOR TO SARGENT & COMPANY, OF NEW HAVEN, CONNECTICUT, A CORPORATION OF CONNECTICUT.

LOCK.

1,255,473.

Specification of Letters Patent.

Patented Feb. 5, 1918.

Application filed April 21, 1917. Serial No. 163,710.

To all whom it may concern:

Be it known that I, JOHN H. SHAW, a citizen of the United States, residing in the city and county of New Haven, State of Connecticut, have invented certain new and useful Improvements in Locks, of which the following is a full, clear, and exact description.

This invention relates to locks and it has particular reference to pin tumbler cylinder locks which are used on the dashboards of automobiles for controlling the ignition and other mechanism. When a movable element which can be actuated from the cylinder lock occupies one position, the mechanism is free for operation, but when it occupies another position such mechanism is locked against operation and cannot be tampered with. In the particular form shown, the pin tumbler cylinder lock is adapted to shift a laterally sliding member mounted at the back of the plate or escutcheon to which the cylinder lock is applied, but the invention can also be used in other connections.

The primary object of the invention is to provide a simple, cheap and efficient cylinder lock construction applicable to the purposes above mentioned, and more particularly to furnish a cylinder lock in which the part to be operated, such as a sliding bolt or the like, can be actuated very conveniently from the front end of the key plug rather than the rear end thereof.

To these and other ends, the invention consists in the novel features and combinations of parts to be hereinafter described and claimed.

In the accompanying drawings,

Figure 1 is a fragmentary front elevation of a dashboard plate equipped with a lock embodying my improvements, said lock being used in connection with the electrical mechanism of an automobile;

Fig. 2 is a rear view of the parts shown in Fig. 1, with the controlling member or slide actuated by the cylinder lock locked in the inoperative position;

Fig. 3 is a fragmentary view of parts shown in Fig. 2, illustrating the slide in the other position;

Fig. 4 is an enlarged elevation of certain parts shown in Fig. 1, with the dash plate or escutcheon broken away;

Fig. 5 is an enlarged end view of the parts shown in Fig. 3;

Fig. 5^a is an enlarged top plan view of the cylinder lock;

Fig. 6 is an enlarged vertical central section through the cylinder lock;

Fig. 7 is a rear elevation of the cylinder lock;

Fig. 8 is an enlarged detail view of the cylinder cam;

Fig. 9 is a view similar to Fig. 4, illustrating a modified construction;

Fig. 10 is a view illustrating a further modified construction; and

Fig. 11 is a section on line 11—11 of Fig. 10.

In the drawings I have shown my improvements applied to the electric controlling mechanism of an automobile, mounted on the dashboard of the car and comprising a plate or escutcheon in which is mounted a cylinder lock which controls a laterally movable slide at the back of the escutcheon or dash plate, which slide when in one position locks the mechanism in an inoperative position, while when the slide is in another position such mechanism can be freely operated. The particular mechanism controlled by the slide forms no part of my invention, and for that reason I have not illustrated or described it in detail. My present invention refers particularly to the cylinder lock construction and to the manner in which the cylinder lock is mounted and arranged relatively to the escutcheon and to the slide or other element.

In the drawings, the dash plate or escutcheon 12 is shown as provided with screw holes 13, by means of which it can be applied to the dashboard or instrument board of the automobile, and slidably mounted at the rear of the plate or escutcheon 12 is a controlling slide 14 guided laterally on the rear surface of the escutcheon in any suitable manner, for example, by means of rivets 15 engaging slots in the slide and permitting a limited longitudinal movement of the

latter. The slide is held at the limit of its movement in one direction by means of a stop spring 16 and it is held at the limit of its movement in the opposite direction by a similar stop spring 16'. The cylinder lock 17 is arranged for the most part at the rear of the escutcheon, but it has a key plug 18 which extends to the front face of the escutcheon where it operates in an opening 19, and this key plug is provided with the usual keyway 20 into which the key 21 may be entered from the front face of the escutcheon. The cylinder lock has a casing 22 in which the key plug 18 is rotatable, and it is provided with sectional spring pressed tumblers 23 of the usual kind, the action of which it will not be necessary to describe. These tumblers are adapted to operate in the usual pin tumbler extension 24 on the casing 22. The cylinder lock is attached to and supported from the escutcheon 12 by means of rivets 25 having shanks which pass rearwardly through holes in the escutcheon and through perforated lugs 26 which extend laterally from the cylinder lock on opposite sides of the front portion thereof. These lugs 26 are usually cast integral with the cylinder lock casing, and their front faces are at such a distance behind the front face of the key plug 18 that when the lugs are held tightly against the rear face of the escutcheon by the rivets 25, the front face of the key plug will be substantially flush with, or will project slightly outward from, the outer face of the escutcheon. The front faces of the lugs are located considerably in advance of the pin tumbler extension 24, and the lugs are offset so as to provide between them a recess 27 at the front of the lock which accommodates a cam 28 for operating the slide 14. This cam 28 has an opening 29 in which the key plug is inserted, said opening being of substantially the same diameter as the key plug, and it is firmly held between the body portion of the lock casing and a collar or flange 29^a on the forward end of the key plug, which collar or flange prevents rearward movement of the key plug relatively to the casing. The key plug is held against forward longitudinal movement, after the parts are assembled, by means of a small metal ring 30 which is sprung into place in an annular groove 31 at the rear end of the key plug, which rear end extends out of the body of the lock to a certain distance, as shown in Fig. 6. When the other parts of the cylinder lock have been assembled the ring 30 is sprung into the groove 31, and it overlies the body of the cylinder to a slight extent, as shown in Fig. 6, so as to prevent forward movement of the key plug relatively to the body or casing. Relative angular movement of the cam and key plug is prevented by a pin 32 driven

radially from the keyway through the upper 65 wall of the key plug, and into a notch 33 with which the cam is provided, said notch 33 communicating with the opening 29 as shown in Fig. 8. At the upper part of the cam between the front of the pin tumbler 70 extension and the rear face of the escutcheon an operating projection 34 is provided, which is adapted to coöperate with talons 35 cut in the lower central part of the plate 14, as shown more particularly in Fig. 4. A 75 stop projection 36 on the cam 28 is adapted to abut the adjacent surface 37 of one of the lugs 26 when the tumblers are lined up with the tumbler sockets and to prevent clockwise rotation of the key plug and cam 80 with respect to Fig. 4, although turning in a counter-clockwise direction is permitted.

In Figs. 1 and 2, I have shown the slide or element 14 in what may be termed the locking position. When it occupies this position, the cam of the cylinder lock occupies the position shown in Fig. 4, and the key can be freely withdrawn owing to the fact that the tumblers are in line with the tumbler sockets. In order to move the slide 14 90 to the unlocked or operating position, the key is inserted and turned about one-eighth of a turn in a counter-clockwise direction with respect to Fig. 4, and the operating projection 34 on the cam by engaging the 95 talons 35 shifts the slide 14 to the limit of its movement toward the left with reference to Fig. 4. In this form, the key cannot be withdrawn while the slide is left in the operating position because when the key plug 100 is turned to the position shown in Fig. 3 the tumbler sections in the key plug are out of line with their sockets in the tumbler extension.

In the form shown in Fig. 9, the cam 28 105 is omitted and a pin 32^a driven into the key plug at the front end of the latter, where it projects out of the body of the lock, takes the place of a cam. This pin 32^a coöperates with a central operating projection 38 on the 110 slide 14^a. In this case, a full revolution of the key is necessary to shift the slide from one position to the other, and the key can be withdrawn with the slide in either of its two positions, as will be understood.

In the modification shown in Fig. 19, the operation is substantially the same as that described in connection with Fig. 9. In this last case a "lazy cam" 39 is interposed between a radial pin 32^b on the key plug and the slide, which in this instance, has talons 40 to receive a radial projection 41 on the "lazy cam."

It will be manifest that I do not limit myself to a construction in which the pin tumbler lock is applied to an escutcheon or mounting plate of the particular type shown in the drawings, inasmuch as the escutcheon

or mounting plate may be constituted wholly or partially by a switch casing or the like.

Various changes may be made in the details of the construction without departing 5 from the scope of the invention as defined in the claims.

What I claim is:—

1. The combination of a plate, a pin tumbler lock having a casing and a key plug, located at the rear of said plate, the main portion of said casing being spaced rearwardly from the plate and the front end of said key plug extending forwardly out of the casing into an opening of said 15 plate, means for securing said pin tumbler lock to said plate, an element to be operated mounted at the rear of said plate, and an operating projection on the forward end portion of the key plug between the pin 20 tumbler lock casing and the plate for engaging said element to operate the same.
2. In a lock, a plate having an opening, a pin tumbler lock at the rear of said plate having a casing and a key plug, said casing 25 spaced rearwardly from the plate and said key plug extending forwardly from the casing into said opening, an element to be operated mounted at the rear of said plate, and means of connection between said key 30 plug and said element connected with the key plug in front of the pin tumbler lock casing.
3. In a lock, an escutcheon having an opening, a pin tumbler lock at the rear of 35 said escutcheon having a casing including a pin tumbler extension and also having a key plug extending forwardly out of the casing into the opening of the escutcheon, an element to be operated mounted at the rear of 40 said escutcheon, and an operating projection for said element on the forward end of the key plug in front of said pin tumbler extension.

4. In a lock, a plate having an opening, 45 an element to be operated located at the rear of said plate but close to the same, a pin tumbler lock at the rear of said plate, having a casing including a pin tumbler extension and also having a key plug extending 50 forwardly out of said casing into the opening of said plate, means at the sides of said pin tumbler lock for securing it to said plate with the body part of the casing and the pin tumbler extension spaced from the rear 55 face of the plate, and an operating projection on the key plug in the space so created, engaging the aforesaid element to operate the same.

5. In a lock, a mounting plate, a cylinder 60 lock at the rear of the same having a casing, and a key plug extending forwardly out of the casing, means at the sides of said casing for securing it to said plate in such a manner that the front of at least a portion of

the casing is spaced rearwardly from said 65 plate at an appreciable distance, an element to be operated, located at the rear of said plate, and means of connection between the forward outwardly projecting end of the key plug and said element.

6. In a lock, an escutcheon having an opening therein, a pin tumbler lock having lugs secured to said escutcheon, the body portion of said pin tumbler lock between said lugs being spaced from the rear surface 75 of the escutcheon, said pin tumbler lock having a key plug extending forwardly out of the body portion of said pin tumbler lock into the opening of the escutcheon, an operating projection on said key plug intermediate the rear face of the escutcheon and the body portion of the pin tumbler lock, and means shiftable by said projection.

7. In a lock, a mounting plate, a pin tumbler lock at the rear of the same having 85 forwardly projecting lugs for securing it to said plate, said pin tumbler lock also having a forwardly projecting key plug extending from the casing out into an opening of said plate, and an operating projection on the 90 forwardly projecting portion of the key plug immediately at the rear of said plate.

8. In a lock, an escutcheon, a pin tumbler lock having its body portion spaced from the rear face of said escutcheon, means for 95 securing said pin tumbler lock to said escutcheon, a key plug in said pin tumbler lock extending forwardly therefrom, through said escutcheon, an element to be operated located at the rear of said escutcheon, and means of connection between said element and the forward end portion of said key plug.

9. In a lock, an escutcheon, a pin tumbler lock having its body portion spaced from 105 the rear face of said escutcheon, means for securing said pin tumbler lock to said escutcheon, a key plug in said pin tumbler lock extending forwardly therefrom, through said escutcheon, an element to be 110 operated located at the rear of said escutcheon, and means of connection between said element and the forward end portion of said key plug, comprising a cam mounted on the forward end portion of the key plug immediately behind the escutcheon and in front of the body portion of said pin tumbler lock.

10. In a lock, a mounting plate having an opening, a cylinder lock at the rear of the same having a casing, a key plug extending 120 forwardly out of the casing, forwardly projecting securing lugs on the casing whereby it is attached to said plate with said casing spaced an appreciable distance from the rear face of said plate, said key plug extending into the opening of said plate, an element to be operated, located at the rear of said plate, and an operating projection

- for said element secured to the forwardly projecting portion of the key plug immediately at the rear of said plate and in front of said casing.
- 5 11. A pin tumbler lock, comprising a body or casing having forwardly projecting securing lugs, and a forwardly projecting key plug extending from the casing between said securing lugs.
- 10 12. A pin tumbler lock, comprising a body or casing having forwardly projecting securing lugs at the sides, a forwardly projecting key plug between said securing lugs, and an operating projection on said key plug between said securing lugs.
- 15 13. A pin tumbler lock comprising a body or casing having a plurality of pin tumblers, a key plug rotatable in said casing and coöperating with said pin tumblers but extending forwardly out of said casing, and an operating projection on the forward end portion of said key plug at the front of said casing.
- 20 14. In a pin tumbler lock, the combination of a casing, forwardly projecting securing lugs on opposite sides of said casing, pin tumblers in said casing, a key plug rotatable in said casing and coöperating with said pin tumblers, said key plug projecting forwardly out of said casing between said securing lugs, and an operating projection on the forward end portion of the key plug between said securing lugs.
- 25 15. In a pin tumbler lock, the combination of a casing, forwardly projecting securing lugs on opposite sides of said casing, pin tumblers in said casing, a key plug rotatable in said casing and coöperating with said pin tumblers, said key plug projecting forwardly out of said casing between said securing lugs, and an operating projection on the forward end portion of the key plug between said securing lugs to limit the swinging movement of said projection.
- 30 16. In a lock, a mounting plate having an opening, a cylinder lock at the rear of said plate having a casing spaced rearwardly from the plate, said cylinder lock also having a key plug extending forwardly out of the casing into the opening of said plate, an element to be operated mounted at the rear of said plate, and means of connection between the key plug and said element, located between the rear face of said plate and the front of said casing.
- 35 17. In a lock, a mounting plate having an opening, a cylinder lock at the rear of said plate having a casing spaced rearwardly from the plate, said cylinder lock also having a key plug extending forwardly out of the casing into the opening of said plate, an element to be operated mounted at the rear of said plate, and means of connection between the key plug and said element, located between the rear face of said plate and the front of said casing.
- 40 18. In a lock, a mounting plate having an opening, a cylinder lock at the rear of said plate having a casing spaced rearwardly from the plate, said cylinder lock also having a key plug extending forwardly out of the casing into the opening of said plate, an element to be operated mounted at the rear of said plate, and means of connection between the key plug and said element, located between the rear face of said plate and the front of said casing.
- 45 19. The combination of a mounting plate, a cylinder lock applied to the rear face thereof and having a key plug, an element to be operated mounted at the rear of said plate, and means of connection between the forward end of the key plug and said element, including a pin driven into an opening in the key plug.
- 50 20. The combination of a mounting plate, a cylinder lock applied to the rear face thereof and having a key plug, an element to be operated, mounted at the rear of said plate, and means of connection between the forward end of the key plug and said element, including a pin driven into an opening in the key plug and a cam operated by said pin.
- 55 21. The combination of a mounting plate, a cylinder lock applied to the rear face thereof and having a key plug, an element to be operated, mounted at the rear of said plate, and means of connection between the forward end of the key plug and said element, including a pin driven into an opening in the key plug, a cam operated by said pin, and stop means for said cam.
- 60 22. In a lock, a mounting plate having an opening, a pin tumbler lock at the rear of the same having a casing including a pin tumbler extension and also having a key plug extending forwardly from said casing into said opening, and an operating projection fixed to the forward end of the key plug between said pin tumbler extension and the rear face of said plate.
- 65 23. The combination of a mounting plate, a pin tumbler lock applied to the rear face thereof and having a forwardly projecting key plug, and an operating cam embracing the forwardly projecting end of the key plug and operated thereby.
- 70 24. In a lock, the combination of an element to be operated, a pin tumbler lock having a casing and a key plug, said key plug extending out of said casing at one end, an operating cam for said element embracing

the outwardly projecting end portion of said key plug, and a radial pin on the key plug coöperating with said cam.

25. The combination of a supporting plate having an opening, a cylinder lock at the rear of said plate having a casing and a key plug extending forwardly out of said casing, the body portion of said casing being spaced rearwardly from said supporting plate, and

said key plug extending into the opening of 10 said plate, a locking device mounted on the forward end portion of the key plug in the space between the casing body and the rear surface of the plate, and means for securing said cylinder lock to said plate.

In witness whereof, I have hereunto set my hand on the 17 day of April, 1917.

JOHN H. SHAW.
